UNITED STATES PATENT OFFICE.

EZRA S. SMITH, OF ATTLEBORO, MASSACHUSETTS, ASSIGNOR TO THE R. F. SIMMONS COMPANY, A CORPORATION OF RHODE ISLAND.

SAFETY DEVICE.

SPECIFICATION forming part of Letters Patent No. 734,142, dated July 21, 1903.

Application filed April 30, 1903. Serial No. 154,986. (No model.)

To all whom it may concern:

Be it known that I, EZRA S. SMITH, a citizen of the United States, residing at Attleboro, in the county of Bristol and State of Massachusetts, have invented a certain new and useful Improvement in Safety Devices, of which the following is a specification, reference being had therein to the accompanying drawings.

10 My invention relates to devices used in connection with watches, lockets, and similar articles for insuring the latter against accidental displacement.

It is sought by my attachment to remedy 15 the annoyance and damage incident to the fall of a watch or similar article from its position intermediate a belt and the wearer's clothing or between any two articles of wearing-apparel where frictional engagement has heretofore of necessity been largely relied upon, especially in hot weather.

20 While particularly adapted to the use of ladies, the structure of my improvement makes it obviously applicable to a gentleman's chain.

25 To the elimination of the above disadvantages my invention is primarily directed; and it consists in the novel construction and combination of parts hereinafter described, and 30 illustrated in the accompanying drawings, wherein—

Figure 1 is a perspective view of my novel device detached, and Fig. 2 a side elevation of the same engaging a watch or locket in 35 operative position.

Like letters of reference indicate like parts throughout the views.

In the drawings, *a* is the head, *b* the bar, which is outwardly bowed, as shown, and *c* 40 the tongue of a watch-swivel engaged through the ring *d* with a watch-chain *e*.

Fixed to the upper portion of the head *a* or integral therewith is an upwardly-directed

post *m*, with a flattened or tongue portion *n* bent outwardly and downwardly into a plane 45 nearly parallel with the body of the swivel, forming in conjunction with the outwardly-bowed portion of the swivel-bar *b* a hook with a restricted entrance-opening *o*. The hook is preferably of a springy consistency to emphasize 50 the tensional pressure upon the material with which it is engaged and extends to a point contiguous to the top of the ring.

The application of my device is set forth in Fig. 2. The watch *p* is pendent between and 55 frictionally engaged by the belt *r* and clothing *s*, and the hook member arches the upper margin of the belt and compresses the latter against the swivel-bar, thereby preventing a release of the watch from its frictional seat 60 either upwardly or downwardly. The hook, moreover, because of its upturned portion, supports the swivel well down within the belt, so that there are no projecting portions liable to catch or become entangled in adjacent articles.

Having described my invention, what I claim as new, and desire to secure by Letters Patent, is—

In a device of the class described the combination with a swivel having a head, a ring attached to the upper end thereof and an outwardly-bowed depending body, of a hook having one end affixed to the head, said hook having an upwardly-bowed portion that extends to a point contiguous to the top of the ring and a depending free spring-tongue that coacts with the outwardly-bowed body to form a restricted entrance-opening.

In testimony whereof I have affixed my signature in presence of two witnesses.

EZRA S. SMITH.
